UNITED STATES PATENT OFFICE.

OLUF G. PETERSEN, OF LOUISVILLE, KENTUCKY.

SHAKER-SCREEN APPARATUS.

1,185,433.

Specification of Letters Patent. Patented May 30, 1916.

Application filed January 6, 1913. Serial No. 740,493.

To all whom it may concern:

Be it known that I, OLUF G. PETERSEN, a citizen of the United States, residing at Louisville, in the county of Jefferson and 5 State of Kentucky, have invented certain new and useful Improvements in Shaker- Screen Apparatus, of which the following is a specification.

This invention involves improvements in 10 and relating to apparatus for screening coal and other products; and the objects and nature of the invention will be readily understood by those skilled in the art in the light of the following explanation of the accompanying drawings illustrating what I now believe to be the preferred mechanical expression or embodiment from among other constructions, arrangements, and combinations within the spirit and scope of the invention.

An object of the invention, is to provide certain improvements in suspended shaker screens with the ends in view of increasing the capacity thereof and decreasing the operating power required as well as the shock transmitted to the screen supporting frame.

A further object of the invention is to provide certain improvements in details of construction, and in combinations and arrangements of parts, whereby a highly efficient and durable shaker screen will be produced.

The invention consists in certain novel features of construction and in combinations 35 and arrangements as more fully and particularly set forth and specified hereinafter.

Referring to the accompanying drawings:—Figure 1, is a side elevation of apparatus involving my invention, dotted lines 40 indicating certain hidden parts. Fig. 2, is a section on the line A—B, Fig. 1. Fig. 3, is a section on the line C—D, Fig. 1. Fig. 4, is a top plan, certain parts being broken away. Fig. 5, shows one of the screen hangers in edge and side elevations. Fig. 5, is a detail elevation showing a modified support for screen hangers. Fig. 7, is a vertical section thereof on the line E—F, Fig. 6. Fig. 8, is a detail elevation of one 50 of the hanger supports of Fig. 1. Fig. 9, is a vertical section on the line G—H, Fig. 8. Fig. 10, is a top plan, and Fig. 11, an edge elevation of one of the pitmen between an eccentric and a screen.

55 The invention particularly contemplates the provision of apparatus to rapidly handle

the large output of coal from the mines and usually to receive the coal from a tipple, and screen and size such coal and deliver the same into railroad cars or other vehicles 60 movable beneath the apparatus.

In the drawings, I show an apparatus in accordance with my invention arranged transversely of and above three sidings, railway tracks, or vehicle passage ways A, B, C. 65 This apparatus comprises a permanent rigid supporting structure or framework composed of a homogeneous mass or body of metal-reinforced concrete or equivalent material. This rigid frame work comprises a 70 pair of spaced usually-parallel elongated longitudinal rigid top side beams or walls 3, arranged in an elevated position above and transversely of the several tracks or vehicle passages A, B, and longitudinally inclined 75 downwardly from their front ends toward their rear ends. These top side walls are designed to support the elevated longitudinally inclined shaker screens arranged in or above the open space between said top 80 beams and longitudinally thereof. These top beams are supported by and connect the upper ends of series of massive heavy vertical side columns 1, 1^a, 1^b, gradually decreasing in height from the high front end column 1, to the low rear end column 1^b. Columns of the opposite series are correspondingly arranged to form pairs of columns between the various tracks or passageways A, B, C. The several columns, (six in the particular example illustrated) rise from the ground and are mounted on suitable foundations designed to properly carry the great weight of the structure. For instance, I show each column rising from a base 5, with 90 said bases and the lower ends of the opposite side columns bound together and rigidly connected by horizontal cross webs 6, running parallel with and arranged between said tracks or passageways. If so desired 95 vertical upwardly extending corner braces or enlargements 4^a, can be formed at the junctions between said webs and the side faces of the columns. The opposite columns 1^a, also the opposite columns 1^b, are tied together at points intermediate their ends by cross webs 7, arranged a distance above and parallel with the webs 6, and I preferably provide vertical enlargements or braces 4^b, at the junctions between these webs and the 100 side faces of the columns.

The upper portions of the two front end

columns 1, are tied together by a horizontal cross web 9, extending between the inner faces of said columns and extended forwardly to constitute a forwardly and laterally projected floor or platform provided with supports or pillars 10, carrying the journal boxes for the shaker screen actuating shaft hereinafter more fully described.

Vertical corner or angle braces 4^c, can be arranged at and between the inner faces of the columns 1, and the inner face of the floor 9. The upper parts of the columns of each side series are also rigidly tied and connected together by horizontal longitudinal side webs, walls or connections 2, joining the side faces of said columns, and preferably located a distance below the longitudinal top side walls or screen supporting beams 3.

Vertically disposed corner or angle braces 20 or enlargements 4, are preferably arranged above and below the webs 2 at the junctions between the same and said columns, and also below the top side walls 3, at the junctions between the same and the columns. I prefer to provide the top elevated longitudinal screen-supporting portion of the frame work with an approximately horizontal cantaliver extension or overhang projecting rearwardly from the rear columns 1^b, over the track or 30 passageway C, and virtually forming a longitudinal rearward continuation of the top side walls 3. This cantaliver extension consists of longitudinal side walls or beams 8, at their outer ends rigidly tied and connected together by cross piece 14, so that the open space between the sides 8, forms a rearward longitudinal continuation of the space between the sides 3. The sides 8, are rigid with the rear end columns and join to the 40 rear sides thereof and are braced and strengthened by the vertical corner braces 4^a, at the junctions between said sides and columns and forming downward enlargements of said sides. . . .

45 Foot ways, platforms, or running boards 13, are arranged throughout the lengths of the opposite side walls or beams 3, and 8, projecting outwardly from the top longitudinal edges thereof and extending across the 50 upper ends of the columns 1^a, 1^b. The cross portion 14, is preferably arranged horizontal and of sufficient width to form a transverse platform or running board connecting the rear ends of the opposite longitudinal 55 platforms 13. These platforms are also formed of concrete in one piece or homogeneous with the sides and columns and having metal reinforcements joining and rigid with the metal reinforcements of connected 60 or adjoining parts of the framework.

The framework described is composed of a homogeneous or single mass of concrete bound together throughout by metal reinforcements with massive columns as indicated for the purpose of providing a shaker

screen support of the necessary rigidity, mass and weight to absorb or overcome the vibrational effect or action of the shaker screen or screens particularly when such screens are carried at the top of such an 70 elevated structure as required for handling a coal mine output and delivering the same to cars on railway tracks. By providing a concrete structure of approximately the arrangement disclosed, permanence, great rigidity and the necessary weight or mass are 75 attained at minimum first cost and at a minimum upkeep expense.

Shaker screen supporting pedestals, pillars or uprights 12, are arranged at intervals along the top sides 3, 8, and rise from the top edges thereof. These pillars 12, can be formed of concrete molded on and with the top walls 3, as shown in Figs. 1, 8 and 9. If so desired, metal brackets 12^a, can be provided for this purpose as shown by Figs. 6 and 7. These brackets have flat bases fitting on the top edges of the walls 3, and vertical flanges 39 fitting the vertical inner faces of said walls and the brackets are secured by 90 vertical and transverse bolts 38, extending through said walls and if so desired, embedded or molded therein.

The upwardly projecting bodies of the brackets carry the horizontal upwardly projecting studs, spindles or journals 36^a, to receive the swingable links or hangers 27, that carry the shaker screens. Where the pillars 12, formed of concrete with the walls 3, are employed, I usually provide fixed transverse 100 bushings or tubes 37, embedded in the concrete and receiving the studs, journals or spindles 36, for the screen links or hangers 27.

In the particular example illustrated, I provide several superimposed screens arranged over and longitudinally of the space between the top walls of the frame work and carried by the hangers or depending links mounted on the spindles 36, or 36^a. 105 The coal is delivered onto the front end of the top screen by a chute 21, usually depending from the coal tipple (not shown). This chute is adapted to receive the coal dumped from the mine cars, or other conveyers, and 110 discharge the same to the shaker screens. I show an upper screen 15, arranged above and carried by and moving with the intermediate screen 16. The screen 16, is arranged over and delivers onto a shaker or 115 sizing pan 17, mounted independently of the screen 16, and reciprocating oppositely with respect thereto. This shaker 17, preferably carries the several chutes 17^a, 17^b, 17^c, arranged between the sides 2 and 3, and 120 the columns 1^a, 1^b, and above the cross webs 7, and designed to deliver coal into vehicles arranged in the passage ways A, B.

Material too large to pass through the perforations of screen 15, is discharged 130

from the lower end of said screen onto a bar screen 19, forming the extended lower end of the shaker or pan 17, and located between the cantaliver extension sides 8. 5 Material too large to pass through bar screen 19, carried by shaker 17, is discharged from the rear end thereof and drops through opening 19^a, at the outer end of the cantaliver extension, and into the 10 car or vehicle located in the trackway C or on a siding arranged in said space C. The material that passes through the bar screen 19, drops onto the chute 17^c, for delivery to the vehicle or railway car on siding in track way B.

15 The material that passes through the perforations of screen 15, drops onto the screen 16, usually having smaller perforations than those of screen 15. The material that 20 passes through the perforations of screen 16, drops onto the pan or shaker 17, for delivery, usually to chute 17^a, and consequently to a vehicle or car on the siding in trackway A, although the shaker 17 is usually 25 provided with doors controlling the delivery of the material to either chutes 17^a or 17^b, and 17^b discharges into chute 17^c. The material that does not pass through the perforations of screen 16, drops from the end 30 of said screen onto the shaker or pan 17, for delivery to the chute 17^b.

35 The longitudinally - arranged reciprocatory members 15, 16, virtually constitute a single or unitary longitudinally inclined shaker member or element, and this element is carried by and arranged on fixed bottom cross bars 29, having projecting opposite end journals extending transversely through the lower ends of swingable hangers or suspension links 27, located beyond the opposite sides of said shaker element and between the same and the hanger supporting pillars rising from frame sides 3 and 8.

40 The part 17, constitutes the lower shaker element, and this element is likewise supported by and provided with bottom cross bars 29^a, having projecting opposite end journals extending transversely through and mounted in the lower ends of another 45 set of swinging links or suspension hangers arranged between the sides of said lower shaker element and the adjacent sides 3, 8, and pillars mounted thereon.

50 In the particular example illustrated, I show the upper shaker element carried by three pairs of oppositely arranged hangers all of the same length and located at the ends and central portion of the element with the points or axes of suspension of said pairs 55 of hangers arranged at different elevations to maintain said element longitudinally inclined downwardly and rearwardly at the required angle. The lower shaker element is shown supported by four pairs of similar 60 suspension links arranged at the ends of the

element and uniformly spaced intermediate points, and the axes or points of suspension of the pairs of links are also arranged at different elevations to maintain said lower element inclined at the required angle. 70

The hangers supporting the several shaker elements are preferably all of the same length between their bearings receiving the suspension journals and their bearings receiving the journals of the shaker elements, and a pair of hangers for the lower shaker element is located immediately below each pair of hangers for the upper shaker element, so that each pillar rising from the frame sides 3, is provided with a 75 pair of hanger suspension journals 36, (or 36^a) arranged in the same vertical plane and spaced a distance apart greater than the length of a hanger. Each hanger is formed with a transverse bearing at its upper end to receive and turn on a fixed suspension journal 36 (or 36^a) and with a transverse bearing at its lower end to receive and turn on the shaker-element-supporting journal of a cross bar 29 (or 29^a). If so desired, 80 the hangers can be provided with roller bearings to receive said journals.

I prefer to make all of the hangers alike and interchangeable, and if so desired, each hanger can be composed of a pair of similar longitudinal sections 34^a, as shown by Fig. 5, longitudinally abutting at their intermediate portions and rigidly yet removably clamped together by transverse bolts 34. Each section is formed at its opposite ends with half journal boxes or bearings, and with an exterior intermediate longitudinal stiffening rib. However, I do not wish to limit all features of my invention to any particular suspension link or hanger construction. 95

Suitable means are provided for simultaneously, uniformly and oppositely reciprocating or oscillating the upper and lower shaker screen elements. For this purpose, I 100 show a horizontal rotary shaft 26, arranged transversely of the frame work, and in the present instance, located in front of columns 1, and carried by boxes on the supports 10, rising from the platform 9. This shaft is provided with driving pulley 23, and at its intermediate portion opposite the open space between the columns 1, is provided with one or more pairs of oppositely 105 arranged eccentrics 24, 24^a. Each eccentric 24, is operatively connected by a pitman 22, to the front end of the upper shaker screen element, while each oppositely arranged eccentric is operatively connected by a pitman 22^a, with the front end of the lower shaker 110 element. 115

The arrangement of the eccentrics and pitmen is such that the opposite pitmen and consequently their respective shaker elements are always moving in opposite direc- 120 125 130

tions with a consequent tendency to equalize the thrust on the eccentric shaft. Each pitman preferably consists of a connecting rod or bar 22^b, at the front end rigidly bolted to the strap of its operating eccentric, and at its rear end directly and rigidly bolted to the front end of the shaker screen element vibrated thereby, approximately as shown by Figs. 10 and 11. This connecting bar 22^b, 5 is preferably composed of a comparatively wide length of tough strong wood reduced in vertical thickness at 22^c, usually near its rear end portion to provide the desired vertical flexibility in the pitman between the 10 eccentric and the shaker element without the necessity of employing the common expensive cross head connection and spring shock absorbers.

An important feature of my invention 20 consists in the manner of hanging the shaker screen elements so that each will have an approximately true pendulum motion. In carrying out this feature of my invention, I proportion the length of each 25 hanger from point of suspension to point of screen support in accordance with the rates of vibration required to propel the lading along the screen. The hangers or suspension links of the screen are the pendulum 30 rods and the screen and its lading constitute the weight of the pendulum, and hence I provide suspension links of such length as to produce a pendulum that when swinging freely will have a rate of swing approximately 35 the same as the rate of vibration required to move the lading along the screen.

A shaker coal screen must vibrate at the rate of approximately one hundred and ten to one hundred and twenty swings per 40 minute, more or less, to keep the screen clear and insure a maximum delivery of wet "run of the mine" coal. I provide suspension hangers or links approximately six inches in length so that in the particular 45 example referred to the screen and links constitute a pendulum that will swing naturally or freely at approximately the rate of ninety swings or vibrations per minute with gravity acting to stop and start the screen 50 at the ending and beginning of each stroke. Now in order to increase this natural pendulum rate of swing to a rate of approximately one hundred and ten to make the screen clear itself of lumps or pieces of lading 55 tending to catch in the screen openings and to overcome friction, I provide the rotary drive shaft with eccentric connection to the screen and rotate this shaft just enough faster than said natural pendulum 60 rate of swing, to slightly increase the rate of movement of the screen as required. For instance, in the example illustrated, I employ a shaker screen seventy two inches wide, suspended by pendulum rods (hang- 65 ers or links) six inches long, forming a

pendulum having a natural or free rate of vibration or swing of approximately ninety per minute, and I couple this screen to eccentrics having approximately a four inch stroke, and I drive the eccentrics at a rate 70 slightly in excess of ninety strokes per minute so as to bring the rate of vibration of the screen up to approximately one hundred and ten per minute.

With such a shaker screen arrangement 75 I am able to separate wet run of mine coal into several grades or sizes at the rate of approximately two hundred to two hundred and fifty tons per hour with a power consumption of only approximately six horse 80 power. This result is attained because of the true pendulum suspension of the screens whereby the action of gravity is mainly relied on to stop and start the screen at the ending and beginning of each stroke, 85 and shock and jar is eliminated to such an extent as to enable me to employ the direct pitman connection from eccentric to screen embodying the bar having a thin or reduced flexible portion to allow the extensive up 90 and down or vertical movement of the screen due to the short radius on which it swings. Also by employing this short true pendulum suspension and the consequent extensive vertical movement of the 95 screen, the transmission of shock and vibration to the supporting frame work is reduced to the minimum, as well as shock and wear on the actuating mechanism.

By employing the framework substantially as disclosed, supporting the shaking screen elements in the elevated exposed positions, all parts of the screening surfaces are readily accessible. The walk ways or running boards 13, are arranged at the top 100 portions of the side walls and the operators or attendants can stand on and move along these boards so as to easily reach any part of the screens and screen surfaces to manipulate the lading and to observe the operation thereof. This feature of easy access to all parts of the screening surfaces is of great importance in the operation of shaker 105 screens of large capacity.

My peculiar suspension system might be 110 employed in connection with a single screen and in connection with screens supported by frameworks of any other construction and material than herein described.

It is also evident that various modifications and departures might be resorted to without departing from the spirit and scope of my invention and hence I do not wish to limit myself to the exact disclosure hereof.

What I claim is:—

1. In combination, a longitudinally inclined shaker screen having pairs of opposite laterally projecting journals, a supporting frame having pairs of opposite screen supporting fixed journals parallel with said 125 130

first mentioned journals, said pairs of fixed journals being progressively arranged in different horizontal planes, short suspension links all of the same length and having 5 bearings mounted on said fixed journals and bearings receiving said screen journals, said links supporting said screen and in connection therewith forming a pendulum having a natural rate of vibration slightly less than 10 the rate of vibration necessary to feed the lading over the screen, an operating shaft having an eccentric operating connection to said screen.

2. In combination, oppositely-arranged 15 side supports provided with laterally projecting studs, a shaker screen, short suspension links all of the same length and depending from and rotatable on said studs and depending at the sides of the screen 20 and pivotally joined thereto on transverse axes to support the screen and its lading, certain of said studs arranged at different elevations to maintain said screen longitudinally inclined, said screen and links 25 constituting a pendulum having a natural rate of swing slightly less than the rate of screen vibration necessary to feed the lading thereover, and means for swinging said screen to slightly increase said natural 30 rate of vibration of such pendulum to the rate necessary to feed the lading thereover, substantially as described.

3. An elongated longitudinally inclined shaker screen, short swinging suspension

links carrying said screen and in connection therewith forming a pendulum having a natural rate of vibration approximately sufficient to feed the lading down the screen, and eccentric operating means for said screen for increasing the rate of vertical 40 throw thereof to clear the screen openings of lading tending to catch therein.

4. In combination, a shaker screen having a path of movement the same as that described by a short pendulum having a natural rate of vibration approximately sufficient to feed the lading down the screen, and operating means applied to said screen for increasing the rate of vertical throw 45 thereof to clear the screen openings of lading 50 tending to catch therein, substantially as described.

5. The method of feeding material along a shaker screen having a natural rate of vibration approximately sufficient to feed 55 the material down the screen and describing a path of movement the same as that described by a short pendulum, which consists in increasing said natural rate of vibration of the screen to increase the rate 60 of vertical throw thereof, substantially as described.

In testimony whereof I affix my signature in presence of two witnesses.
